UNITED STATES PATENT OFFICE.

PHILIP Y. FULLERTON, OF MOORE, TEXAS.

ATTACHMENT FOR BUGGY-TOPS.

No. 914,263.

Specification of Letters Patent. Patented March 2, 1909.

Application filed October 6, 1908. Serial No. 456,373.

To all whom it may concern:

Be it known that I, PHILIP Y. FULLERTON, a citizen of the United States, residing at Moore, in the county of Frio and State of Texas, have invented a new and useful Attachment for Buggy-Tops, of which the following is a specification.

This invention relates to storm shields or curtains for buggies and similar vehicles and has for its object to provide a comparatively simple and inexpensive device of this character especially designed for attachment to the hood of a buggy top and capable of being extended downwardly in front of the dashboard so as to protect the occupant of the vehicle from the direct rays of the sun in summer, and from rain and snow in winter.

A further object of the invention is to provide means for locking the shield or curtain in different positions of adjustment, and means for automatically returning the curtain to inoperative position when the locking means is released.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification:—Figure 1 is a perspective view of a portion of a buggy provided with a storm shield or curtain constructed in accordance with my invention.

Fig. 2 is a detail transverse sectional view of the upper portion of the hood or cover of the buggy showing the manner of mounting the shield or curtain in position thereon. Fig. 3 is a detail longitudinal sectional view of a portion of the front top bow of the buggy.

Similar numerals of reference indicate corresponding parts in all of the figures of the drawings.

The improved storm shield or curtain forming the subject matter of the present invention is principally designed for attachment to the folding tops of buggies, carriages and similar vehicles and by way of illustration is shown in connection with a buggy top of the ordinary construction in which 5 designates the body of the vehicle and 6 the side bows carrying the hood or cover, indicated at 7.

The device comprises a yoke or frame 8 preferably formed of a single piece of metal and having its opposite ends pivotally mounted at 9 in suitable clips 10 secured to the side bows of the vehicle top, as shown. The forward top bow 11 of the hood 7 is cut away and the terminals of said top bow connected by spaced transverse bars 12 forming an intermediate chamber 13 in which is mounted for rotation a spring actuated roller 14. The roller 14 is journaled at 15 in the adjacent terminals of the forward top bow so as to be completely housed beneath the cover or hood 7.

Secured to the roller 14 is one end of a strip of canvas, rubber or other impervious material 16, the opposite end of which is secured in any suitable manner to the closed end of the frame 8, said strip forming a shield or curtain and serving to protect the occupant or occupants of the vehicle from the direct rays of the sun in summer and from cold and driving snow in inclement weather. As a means for locking the frame 8 in different positions of adjustment the side members of the frame 8 are provided with segmental plates 17, the free ends of which extend through guides or keepers 18 carried by the front bows 6. Threaded in the guides or keepers 18 are clamping screws 19 which bear against the plates 17, these clamping screws being preferably provided with winged heads so that the same may be conveniently manipulated to lock the curtain 90 in adjusted position. It will thus be seen that the occupant of the vehicle, without leaving the latter, may move the curtain 16 to different positions of adjustment by loosening the clamping members 19 and exerting 95 a slight downward pressure on the frame 8, the frame being locked in adjusted position by tightening the screw 19, as before stated.

In order to move the frame 8 to elevated or inoperative position, it is merely necessary 100 to release the clamping members 19 when the spring in the roller 14 will exert a longitudinal pull on the curtain 16 and thus automatically move the frame 8 into engagement with the top bow 11 and in which position the curtain or shield 16 will encircle the roller 14 and be entirely housed beneath the cover 7.

Attention is here called to the fact that the frame 8 is preferably of sufficient length to permit the closed end of the latter to pass 110 over the top of the dash-board 20 when the frame is in its lowest position of adjustment,

said dash-board serving to assist in locking said frame in lowered position.

When the frame is in the dotted line position shown in Fig. 1 of the drawings, the 5 shield or curtain 16 will form a complete housing or protection to the occupant of the vehicle and when in the position shown in full lines will form a shed or canopy to protect the occupant of the vehicle from the 10 direct rays of the sun.

The device may be made in different sizes and shapes and used in connection with buggies, carriages and other vehicles provided with either stationary or folding tops.

15 Having thus described the invention what is claimed is:—

1. The combination with a vehicle top including the side and top bows, one of the top bows being cut away to form a chamber, of 20 a frame pivotally mounted on the side bows, keepers spaced from the pivoted end of the frame, segmental guides secured to the frame and operating within the keepers, a spring actuated roller mounted for rotation 25 in the chamber, a curtain forming a flexible connection between the spring roller and free end of the frame, and clamping devices piercing the keepers and engaging the segmental guides for locking the frame in different 30 positions of adjustment.

2. The combination with a vehicle including the top and side bows and having its

forward top bow cut away, transverse bars connecting the cut away portions of the top bow and spaced apart to form an intermediate chamber, clips secured to the side bows, a substantially U shaped frame pivotally mounted in the clips, keepers spaced from the clips, a spring roller disposed within the chamber and journaled in the adjacent 35 ends of the forward top bow, a curtain forming a flexible connection between the roller and the free end of the frame, segmental guides secured to the frame and slidably mounted in the keepers, and clamping screws piercing the keepers and bearing against the guides for locking the frame in different positions of adjustment.

3. The combination with a vehicle top including the side and top bows, one of the top bows being cut away to form a chamber, of 50 a frame pivotally mounted on the side bows, a spring actuated roller mounted for rotation in the chamber, a curtain forming a flexible connection between the spring roller and frame, and means for locking said frame in different positions of adjustment.

In testimony that I claim the foregoing as my own, I have hereto affixed my signature in the presence of two witnesses.

PHILIP Y. FULLERTON.
